HOBBY HORSE

Stanley Goldfarb, 98 Havilands Lane,
White Plains, N.Y.

Filed Jan. 31, 1963, Ser. No. 73,388

Term of patent 14 years

(Cl. D34—15)

FIG. 2

FIG. 1 is a side elevational view of the hobby horse, showing my new design, the side opposite FIG. 1 being substantially a mirror image thereof the interior walls of the rockers being substantially mirror images of the exterior walls shown in said figure;

FIG. 2 is a rear elevational view of the hobby horse; and

FIG. 3 is a front elevational view of the hobby horse.

I claim:

The ornamental design for a hobby horse, as shown and described.
